UNITED STATES PATENT OFFICE.

FREDERICK W. SCHEIDENHELM, OF PITTSBURGH, PENNSYLVANIA.

FLASH-BOARD CONSTRUCTION FOR DAMS.

1,202,228.

Specification of Letters Patent. Patented Oct. 24, 1916.

Application filed June 19, 1915. Serial No. 35,086.

To all whom it may concern:

Be it known that I, FREDERICK W. SCHEIDENHELM, a citizen of the United States, residing at Pittsburgh, in the county of 5 Allegheny and State of Pennsylvania, have invented certain new and useful Improvements in Flash-Board Construction for Dams, of which the following is a specification, reference being had to the accompanying drawings.

The present invention pertains broadly to a new and useful improvement in flash-board construction for dams and has particular reference to improvements in flash- 15 boards of the so-called collapsible type, which are designed to "fail" in case the water impounded by the dam rises to a dangerous height.

It has been proposed in prior patents, 20 and in some instances carried into practice, to equip the dam with a flashboard which is adapted to "fail" when the impounded water reaches a predetermined height, such failure being provided for by mounting the 25 flashboard for swinging movement and accompanying it by springs or equivalent yieldable elements designed to resist the swinging of the flashboard until the pressure of the impounded water reaches a predetermined point.

The flashboards of the collapsible type as hitherto built or designed have, however, been found to be open to several objections. In the first place, the cost of installation is 35 unduly great. Again, certain flashboards of this type (especially those supported by pins of the kind heretofore used) are not adapted to "fail" completely and reliably as soon as the water reaches a dangerous height but merely bend or tilt somewhat, allowing a part of the impounded water to flow over the dam but not entirely clearing the crest of the dam or spillway. As a result excessive flood heights are not as effectively guarded against by flashboards of 45 the latter type as would be the case were the flashboards designed to "fail" completely, allowing the impounded water to flow over the spillway or crest of the dam 50 without any obstruction on part of the flashboard or the flashboard supports.

In recognition of the above objections to the collapsible flashboards at present in use, it is, therefore, the principal object of the present invention to provide a flashboard, 55 and more particularly a flashboard support, which is of utmost simplicity in construction, may be manufactured and installed at an unusually small cost, and is designed to "fail" completely and wash over the crest 60 of the dam at a predetermined height, thus allowing the impounded water to spill directly over the crest of the dam until it subsides to a normal level.

A further and more specific object of the 65 invention is to provide a flashboard which consists generally in a wall of suitable material and a plurality of supporting pins which are anchored at their lower ends in the crest of the dam or spillway, and extending approximately to the height of the flashboard, are so constructed that they will maintain the wall in approximately its original position until the impounded water reaches the predetermined level, and will 70 then snap or break off at the dam or spillway crest, thus permitting the impounded water to sweep the flashboard over the dam.

A still further specific object of the invention is the provision of flashboard supports in the form of steel pins having a relatively high proportion of carbon in their composition so that by proper hardening they become stiff and yet not too brittle, and will, therefore, resist any bending or 85 flexing of the flashboard until the water reaches the predetermined level, at which level the pressure of the impounded water against the flashboard will cause the pins to break or snap off.

The above, and other incidental objects of a similar nature, which will be herein-after more specifically treated, are accomplished by such means as are illustrated in the accompanying drawings, described in 95 the following specification, and then more particularly pointed out in the claims which are appended hereto and form a part of this application.

With reference to the drawing, wherein is 100 illustrated the preferred embodiment of the invention, as it is reduced to practice, the

figure is a transverse vertical section taken through the crest of the spillway section of a dam of the hollow type and illustrating the flashboard support of the present invention mounted thereon and supporting a wooden flashboard.

Before taking up the detailed description of the drawing, it is desired to explain first that, while the flashboard support has been shown in connection with a dam of the hollow type, it may, nevertheless, be employed with equal efficiency with a solid dam since the particular design of the dam and the materials used in its construction are matters of no consequence to the operation of the flashboard support.

The flashboard, or wall, designated generally by the letter A, is mounted upon the spillway crest of the dam B to extend longitudinally therealong and in vertical alignment with the crest of the spillway. In this connection, it is to be particularly explained that while the flashboard is preferably disposed in vertical alignment with the spillway crest of the dam, it may be differently located without departing in any way from the spirit of the present invention. The flashboard or wall A as shown consists of wooden boards 10. The wall A may however, be constructed of metal or concrete or any other suitable material or materials. The materials which are employed in making the wall A are not within the scope of the present invention. The wall is, as shown, supported in a vertical position by means of a plurality of round pins 11, which are preferably located against the down-stream face of the wall A. The pins may be embedded in the wall in case this member is built of concrete or may be passed through bores formed in the wall in case this member is made of planking. Also, if desired and deemed expedient, the pins may be disposed on the up-stream face of the member A and tied into this member by any suitable means.

The pins need not necessarily be of circular cross section, but the circular cross-section is preferable because a round pin offers the same resistance to stress no matter whether a given point in the pin 11 is on the up-stream side or the down-stream side or any other side of the pin.

The lower ends of the pins are inserted in the sockets 12 (preferably formed of pipe) in the spillway crest of the dam. In an initial construction the sockets are embedded in the concrete at the time the concrete is placed. When the present invention is applied to an existing dam in which no sockets have previously been provided, however, proper sockets are constructed by drilling receiving bores in the spillway crest of the dam, in a manner which will be readily appreciated by those skilled in the art.

65 I desire now to explain that the method

of treating the supporting pins is a special feature of my invention. In the first place, the pins are made of steel which must contain a relatively large proportion of carbon. This is necessary because the pins are later to be hardened, which it is impossible to do if the carbon content of the steel is too low. On the other hand, the carbon content must not be too great, for with an excessive carbon content the pins would become too brittle. I prefer to use open hearth steel with a carbon content between 0.40% and 0.80%. Likewise the sulfur and phosphorus contents of the steel must not be excessive, for excessive amounts of these constituents also will make the pins too brittle for the purpose. I prefer that the sulfur and phosphorus contents should each not exceed 0.05%.

Pins composed of steel of the chemical characteristics above described are then hardened by, first, heating them in a forge, or by other suitable means, preferably to a "cherry red" color, and then promptly plunging the bars thus heated into water or other suitable cooling liquid. Under ordinary conditions the pins need to be hardened for only a relatively short distance, as shown in the figure at 13, above and below that point in the pins which will (when in place) be opposite the top of the socket 12, it being intended that the pins shall break or snap off at the top of such sockets or anchorages. In special cases, however, it may be advisable to thus harden the pins throughout that portion of their length which projects above the socket or anchorage, or even throughout their entire length.

The result of such hardening is that the pins will resist bending or flexing in themselves (and hence in the wall A) until the stress in the pins reaches such a point that the pins will "fail" by breaking or snapping off. By proper control of the constituents of the steel of which the pins are made, as hereinabove described, the pins will break at a predetermined stress and will not be so brittle that their behavior will be erratic and their "breaking points" not approximately uniform. The predetermined stress at which the pins will break, with little or no previous permanent deflection, is such that it will be developed by the impounded water when the same has risen to the predetermined elevation.

It is to be noted that because of the fact that the projecting or upper portions of the pins 11 act as cantilevers, the stress in the pins is greatest at the lower end of projecting portion, viz, at the top of the socket or anchorage. Hence it is at this point that the pins will break. The breaking or failure of the pins will, therefore, not merely allow the wall A to be washed over the spillway crest of the dam, but will clear the spillway

crest of any obstruction due to the pins themselves. The result is that the spillway or flood discharging capacity of the dam is correspondingly increased. After the flood 5 has sufficiently subsided, the lower ends of the pins still remaining in the sockets, or anchorages, are removed by using tongs, or other suitable means. New pins, of the same characteristics and previously hardened, as 10 above described, may then be inserted and a new wall A erected, or the original wall A replaced, so as to again impound the water to the desired elevation, greater than that of the spillway crest of the dam.

15 An advantage due to my invention should be particularly noted, namely, that the deflection in the supporting pins prior to breaking is negligible in amount, and that, therefore, if the impounded water should rise to 20 an elevation nearly equal to the elevation at which the pins would break, but should thereupon subside to a normal level, the flashboard would resume approximately its original vertical position. On the other 25 hand, supporting pins not hardened as above described would either have been bent so much as not to return to their original position (and would, therefore, not be suitable for further use) or, if they had not deflected 30 appreciably, would be so strong that they would not break at so low an elevation of impounded water as would have caused the failure of pins with the characteristics, and hardened, as above described.

35 The diameter of the round pins 11 and the carbon content thereof are suitably proportioned according to the spacing of the pins 11, the height of the wall A, the elevation of the impounded water at which it is intended that the pins (and hence the wall A) 40 shall "fail", and any other pertinent conditions. It is immaterial whether or not the predetermined water elevation, at which failure of the flashboard is intended to occur, 45 is such as to cause part of the impounded water to flow over the top of the flashboard.

While I have illustrated and described the flashboard support as being particularly 50 adapted for use in supporting a flashboard on the spillway crest of the dam, I desire it to be understood that the invention is not limited to such application. Thus, such supports may be advantageously employed in 55 anchoring a temporary dam to its foundation, in order to provide for the sudden "failure" of the dam when the impounded water reaches a danger level, or in supporting a flashboard or other obstruction in a 60 channel or waterway likewise in order to provide for "failure" under predetermined conditions.

What is claimed, is:—

1. The combination with a supporting 65 base, of a damming element mounted there-

on, and a plurality of metallic pins secured at their lower ends in the supporting base and engaging at their upper portions with the damming element for holding the same against down-stream movement on the supporting base, said pins being formed of relatively high carbon steel, whereby they are stiff and brittle and are, therefore, adapted to snap off, causing the failure of the damming element when the impounded water 75 reaches a predetermined elevation.

2. The combination with a dam, of a flashboard consisting of a wall mounted on the dam to extend longitudinally on the crest thereof, and a plurality of metallic pins 80 anchored at their lower ends in the dam, and engaging with the flashboard for anchoring the same in position on the dam, said pins being formed of relatively high carbon steel, whereby they are brittle and 85 relatively inflexible so that they will rigidly anchor the flashboard upon the dam until the moment at which the impounded water reaches a predetermined elevation at which time the pins are adapted to snap off by 90 reason of their brittleness, to cause the failure of the flashboard and to permit this member to be carried off the dam in a downstream direction by the impounded water spilling over the dam.

3. The combination with a supporting base, of a damming element mounted thereon, and a plurality of metallic pins secured at their lower ends in the supporting base and engaging at their upper portions with 100 the damming element for holding the same against downstream movement on the supporting base, said pins being formed of relatively high carbon steel, each of said pins being hardened at that portion which lies at 105 and immediately above and below the surface of the supporting base, by heating followed by immediate rapid cooling.

4. The combination with a supporting base, of a damming element mounted thereon, a plurality of sockets formed in the supporting base and opening through the upper surface thereof, and a plurality of metallic pins having their lower portions seated in the said sockets and their upper portions 115 engaging with the damming element for holding the same against downstream movement on the base, said pins being formed of relatively high carbon steel, and being hardened by heating followed by immediate 120 rapid cooling, the hardened portions of the pins extending a slight distance above and below the upper surface of the supporting base.

5. The combination with a supporting 125 base of a damming element mounted thereon, a plurality of metallic sockets embedded in the supporting base and opening through the upper surface thereof, and a plurality of brittle metallic pins having their lower 130

portions seated in the sockets and their upper portions engaging the damming element for supporting the same against down stream movement on the base, the upper ends of said sockets constituting rigid abutments for the intermediate portions of the pins whereby the pins will tend to snap off at points located at or immediately adjacent to the upper surface of the supporting base

when the damming element is subjected to a predetermined down stream pressure.

In testimony whereof I hereunto affix my signature in the presence of two witnesses.
